[57] CLAIM

The ornamental design for a consumer IR thermometer, as shown and described.

DESCRIPTION

FIG. 1 is a top plan view of the consumer IR thermometer showing our new design;
FIG. 2 is a side elevational view of the consumer IR thermometer of FIG. 1;
FIG. 3 is a bottom plan view of the consumer IR thermometer of FIG. 1;
FIG. 4 is a front view of the consumer IR thermometer of FIG. 1;
FIG. 5 is a side elevational view of the consumer IR thermometer of FIG. 1;
FIG. 6 is a rear view of the opposite side of the consumer IR thermometer of FIG. 1;
FIG. 7 is a side view of the open position of the consumer IR thermometer of FIG. 1; and,
FIG. 8 is a face view of the consumer IR thermometer of FIG. 7.
The broken line showing is for illustrative purposes only and forms no part of the claimed design.
